UNITED STATES PATENT OFFICE.

ROY W. KUMLER, OF LOS ANGELES, CALIFORNIA.

AUTOMOBILE HOOD CONSTRUCTION.

Application filed July 21, 1920, Serial No. 397,905. Renewed April 5, 1923.

To all whom it may concern:

Be it known that I, ROY W. KUMLER, a citizen of the United States, residing at Los Angeles, county of Los Angeles, and State of California, have invented a new and useful Automobile Hood Construction, of which the following is a specification.

My invention relates to automobiles, trucks, tractors, etc., in which the engine is placed beneath a hood having hinged members on either side which may be lifted to give access to the engine.

The principal object of my invention is to provide a water tight hood construction which will be much cheaper than the ordinary form of hinged joint and which will give a flush appearance along the top of the hood when closed.

Referring to the drawing,

Fig. 1 is a perspective view of the parts before assembling.

Fig. 2 is a cross section through the joint, one of the side members being partially lifted.

Fig. 3 is a similar view of the same member lifted to a further degree.

Fig. 4 is an alternate form of joint.

Fig. 5 is a view of a hood as seen from above as equipped with my invention.

In the form of the invention illustrated in this drawing, 11 is the radiator and 12 is the cowl of an automobile, the space between the radiator and the body being filled with sheet steel hood members 14 and 15, these members being fastened at their lower edges by any convenient means, not shown.

In the form of the invention illustrated in Figs. 1 to 3 inclusive, the edges of the members 14 and 15 are turned over as shown at 20 passing through a slot 21 in a restraining member 22. The restraining member 22 is formed of sheet metal having lips 23 and 24 at either side of the slot 21, the slot being enlarged as shown at 25 in Fig. 1 at either end. A trunnion 30 is provided having a body of proper size to fit inside the restraining member 22. The parts are assembled by placing one of the trunnions, not shown in Fig. 1 in the right hand end of the restraining member 22, this end also not being shown in that figure. Members 14 and 15 are then slipped into the left hand end of the slot 21 and the trunnion 30 is slipped inside the opening 25 and into an opening 32 formed in the members 14 and 15. The trunnion 30 is provided with grooves 33,

these grooves being designed to prevent the members 14 and 15 from dropping through the slots when these members are raised. A tongue 40 is provided on the trunnion 30 to separate the edges of the members 14 and 15 as shown in Figs. 3 and 4. If desired, the edges of members 14 and 15 may be bent over and cut away as shown at 32 in Fig. 1. As the members 14 and 15 are raised, their edges at either end rest in the grooves 33 which support the weight of the members 14 and 15.

If desired, the members 14 and 15 may have their edges crimped over as shown in Fig. 4.

I claim as my invention:

1. An automobile hood construction comprising a restraining member having parallel lips separated by a slot, means for pivoting each end of said restraining member in the frame of the automobile, two sheet steel members having their edges passing through said slot and hooked around said lips, and means for separating the edges of said sheet steel members.

2. An automobile hood construction comprising a restraining member having parallel lips separated by a slot, means for pivoting each end of said restraining member in the frame of the automobile, two sheet steel members having their edges passing through said slot and hooked around said lips, and means against which the edges of said sheet steel members abut and slide to prevent them from touching each other or dropping through said slot as they are moved towards each other.

3. An automobile hood construction comprising a restraining member in the form of a trough having parallel upper edges separated by a trough, two sheet steel members having their edges bent over to form hooks engaging the parallel upper edges of said restraining member, two trunnions one in each end of said restraining member, each trunnion having a cylindrical portion on which the trunnion and restraining member are supported, and means formed on said trunnion for preventing the edges of said sheet steel members from touching each other.

4. An automobile hood construction comprising a restraining member in the form of a trough having parallel upper edges separated by a trough, two sheet steel members having their edges bent over to form

hooks engaging the parallel upper edges of said restraining member, two trunnions one in each end of said restraining member, each trunnion having a cylindrical portion on which the trunnion and restraining member are supported, and two projections, one on each trunnion extending between and separating the edges of said sheet steel members.

5. An automobile hood construction comprising a restraining member in the form of a trough having parallel upper edges separated by a trough, two sheet steel members having their edges bent over to form hooks engaging the parallel upper edges of 10 said restraining member, two trunnions one in each end of said restraining member, each trunnion having a cylindrical portion on which the trunnion and restraining member are supported, said trunnions being hollowed 15 out to form supporting grooves for said sheet steel members when same are moved towards each other, and means formed on 20 said trunnion for preventing the edges of

said sheet steel members from touching each other.

25

6. An automobile hood construction comprising a restraining member in the form of a trough having parallel upper edges separated by a trough, two sheet steel members having their edges bent over to form 30 hooks engaging the parallel upper edges of said restraining member, two trunnions one in each end of said restraining member, each trunnion having a cylindrical portion in which the trunnion and restraining member 35 are supported, said trunnions being hollowed out to form supporting grooves for said sheet steel members when same are moved towards each other, and two projections, one on each trunnion extending between and separating the edges of said sheet steel members.
